UNITED STATES PATENT OFFICE.

JEREMIAH P. JOHNSON AND GEORGE W. MASON, OF DETROIT, MICHIGAN.

DOOR-LATCH.

1,262,054.

Specification of Letters Patent. Patented Apr. 9, 1918.

Application filed December 27, 1915. Serial No. 68,740.

To all whom it may concern:

Be it known that we, JEREMIAH P. JOHNSON and GEORGE W. MASON, citizens of the United States of America, residing at Detroit, in the county of Wayne and State of Michigan, have invented certain new and useful Improvements in Door-Latches, of which the following is a specification, reference being had therein to the accompanying drawings.

The invention relates to latches particularly designed for application to the doors of automobiles and other vehicles, and it is the object of the invention to obtain an exceedingly simple construction, efficient in its operation and one which can be manufactured at low cost.

In the drawings:

Figure 1 is an elevation showing the latch as applied to an automobile door;

Fig. 2 is an enlarged section therethrough; and

Figs. 3 and 4 are perspective views of the latch and keeper members respectively.

A is the door frame and B is the adjacent frame of the body. C is a keeper which is attached to the body-frame and has a projecting portion D with a beveled forward face E. F is a recessed plate attached to the door frame, the recess being adapted to receive the projecting portion D of the keeper in the closed position of the door. G is a bent rod having a portion G' extending upward through an aperture H in the recessed portion of the plate F, said portion G' having a beveled face G². The rod G is also provided with an upwardly-extending portion G³, which passes through the top rail of the door frame and is threaded to engage a knob I. J is a sleeve or thimble fitting in an aperture in the top rail A' of the door frame, being apertured in the bottom for the passage of the rod G³ and at its upper end receiving the shank of the knob I. K is a

spring sleeved upon the portion G³ of the rod G arranged within the sleeve or thimble J and having its upper end bearing against the rod I.

With the construction as described, the spring K will normally draw the rod G upward so as to project the portion G' into the recess F' and in the path of the beveled projection D of the keeper. When, however, the door is slammed shut the beveled faces of the member D and the portion G' will cause the depression of the latter against the tension of the spring K until the member D passes beyond the portion G and the latter is free to be raised by the spring K. In this position the door will be effectually locked, but it may at any time be released by the depression of the rod I which lowers the rod G and withdraws the portion G' from the path of the keeper D.

What we claim as our invention is:—

The combination with an automobile body and door, of a keeper projecting from said body, a member secured to said door and having a recess adapted to receive said keeper when the door is closed, said member having a guiding hole therein, a rod having a portion extending from below through said hole into said recess, an offset portion and an operating portion extending upwardly to the top rail of said door, means for normally raising said rod through said guide hole into the path of said keeper, said keeper and rod having coöperating beveled faces for depressing the rod upon the closing of, the door.

In testimony whereof we affix or signatures in presence of two witnesses.

JEREMIAH P. JOHNSON.
GEORGE W. MASON.

Witnesses:

JAMES P. BARRY,
PHYLLIS COBURN.
